(No Model.)

J. B. BIRDSELL, L. H. BRATT & W. F. WETMORE.
STEAM BOILER.

No. 326,833.

Patented Sept. 22, 1885.

UNITED STATES PATENT OFFICE.

JOSEPH B. BIRDSSELL, LEVI H. BRATT, AND WILLIAM F. WETMORE, OF SOUTH BEND, INDIANA.

STEAM-BOILER.

SPECIFICATION forming part of Letters Patent No. 326,833, dated September 22, 1885.

Application filed March 19, 1885. (No model.)

To all whom it may concern:

Be it known that we, JOSEPH B. BIRDSSELL, LEVI H. BRATT, and WILLIAM F. WETMORE, of South Bend, in the county of St. Joseph and State of Indiana, have invented certain new and useful Improvements in Steam-Boilers; and we do hereby declare that the following is a full, clear, and exact description thereof, reference being had to the accompanying drawings, and to the letters of reference marked thereon, which form part of this specification, in which—

Figure 1 represents a perspective view of the boiler. Fig. 2 is a vertical transverse section of the same. Fig. 3 is a vertical longitudinal section through the boiler. Fig. 4 is a horizontal section showing the relation of the inner and outer shells and intermediate diaphragm. Fig. 5 represents a modification 20 of one of the tubes.

The invention relates to improvements in steam-boilers, and has for its main object to provide means whereby a very large amount of heating surface may be exposed to the direct action of the fire, so as to economize both in time and fuel when raising steam.

A further object of the invention is to construct the boiler in such manner that all impurities in the water, such as usually form 30 crustations, will be deposited in chambers made for their reception, and whence they can be readily removed.

The invention consists in the construction and novel arrangement of parts hereinafter 35 described, and pointed out in the appended claims.

Referring to the accompanying drawings by letter, A designates the outer shell or casing of the boiler, of pyramidal shape, and provided on top with the steam-dome and safety-valve A', of usual construction.

The side edges of the outer shell are made with longitudinal bulges a a, so as to form, with the inner shell hereinafter described, the lateral longitudinal eddy chambers or spaces, B B, the purpose of which is hereinafter explained.

C is the inner shell, of pyramidal form and standing within the outer shell, the flanged 50 edges c c' of the shells being properly packed

and bolted together to make the space between the shells water-tight.

The crown-sheet D is constituted by the upper horizontal portion of the inner shell, as shown, and above the crown sheet is the steam-space D'.

The interior of the inner shell forms the fire-box E, which is provided with the grate E' and the chimney or flue e, to carry off the products of combustion, the said flue passing through the outer shell.

The grate E' is placed some distance above the level of the eddy-chambers B, for a purpose hereinafter explained.

F is an intermediate continuous diaphragm, 65 preferably of sheet-zinc, surrounding the inner shell, but open above and below. The said diaphragm divides the space between the shells into the outer space, f, and the inner space, f', which open into each other at top 70 and bottom only. f' f' are stay rods or bolts, by means of which the diaphragm is secured in position between the shells.

G G are tubes, which have their upper ends passing through the crown-shell, and rising to 75 the level of the ordinary water-line in the steam-space, and their lower ends below the grate connected by coupling-pieces g g to short horizontal tubes G', which penetrate the inner shell and enter the space f'. The 80 tubes G form two series, arranged on opposite sides within the fire-box, as shown.

H H are man-holes in the ends of the outer shell, by means of which access is had to the eddy-chambers B, and H' is the ash-pit below 85 the grate.

I is the door of the fire-box, covering the outer orifice of a tube connecting the shells and running through the diaphragms and spaces f and f'.

J is a proper steam-pipe, running from the steam-space to connect to the steam-chest of a cylinder in the usual manner.

When a fire is lighted, the water in the inner space, f', and tubes G will be nearest thereto, and will be most heated. It will also be heated most near the bottoms of the space and the tubes, and will consequently flow upward therein to the steam-space. This upward current will be returned downward, as shown by 100

the arrows, through the space *f*, to gain additional heat as it again passes up through the inner space and pipes.

Now, as the united capacity of the tubes and inner space is considerably greater than the capacity of the outer space, the water will necessarily flow upward through the former at a slower rate than downward through the latter. It will consequently be longer exposed to the heating-surfaces, and will be more quickly returned thereto by the outer space than in the usual construction, so that both time and fuel will be economized.

The water will be coolest at the bottom of the outer space, *f*, below the fire-grate—that is, in the eddy-chambers *B*—so that it will be more liable to deposit there dissolved matter; moreover, the shape of the said chambers causes an eddy in them which partly neutralizes the current of water, and causes suspended matter to be deposited. The chambers are cleaned out through the man-holes *H*.

The boiler is adapted to be used with either a stationary or portable engine, its shape making it stand steady when used with the latter.

We are aware that boilers of a pyramidal shape and provided with heating-tubes in the fire-box have been used, and therefore do not claim such broadly.

The couplings *g* may, if desired, be omitted,

and each tube *G* be made in one piece with a tube, *G'*, and bent to the shape of the coupling at a proper point, as shown in the drawings. The lower end of the tube may be secured to the inner shell by a bush-coupling.

35

Having described our invention, what we claim is—

1. The combination of the shells *A* *C*, diaphragm *F*, steam-space *D'*, and coupled tubes *G* and *G'*, with the fire-box *E*, provided with the grate *E'*, situated at a level above that of the lower ends of the tubes *G*, substantially as specified.

2. In a pyramidal boiler, the combination, with the inner shell, *C*, and diaphragm *F*, fire-box *E*, provided with the grate *E'* and steam-space *D'*, of the outer shell, *A*, provided with the bulges *a a*, which, when the said outer shell is in place, form the eddy-chambers *B* *B*, provided at their ends with man-holes *H*, substantially as and for the purpose specified.

45

In testimony that we claim the foregoing as our own we affix our signatures in presence of two witnesses.

JOSEPH B. BIRDSELL.

LEVI H. BRATT.

WILLIAM F. WETMORE.
